United States Patent Office

Des. 185,579
Patented June 23, 1959

185,579

PORTABLE SHELTER OR SIMILAR ARTICLE

Leo P. Sklar, Oak Park, Mich.

Application May 19, 1958, Serial No. 50,944

Term of patent 14 years

(Cl. D13—1)

The figure is a perspective view of a portable shelter showing my new design.

The external top and rear portions not shown are substantially the same as the internal portions shown.

I claim:

The ornamental design for a portable shelter or similar article, as shown and described.
